SHIPPING CARTON

Ernst F. Lang and Andrew J. Maas, Detroit, Mich.

Application December 23, 1933, Serial No. 703,780

7 Claims. (Cl. 206—65)

This invention relates to shipping cartons and particularly to cartons for packing and shipping vacuum cleaners.

An object of the invention is to provide a set of fibre board packing elements, each designed to engage a certain portion of a vacuum cleaner, and jointly adapted to definitely position the vacuum cleaner within a shipping carton, and to absorb such shocks and stresses as the shipment

will encounter in normal transit.

Another object is to secure such a set of packing elements to a fibre board supporting sheet so as to form a packing unit, positively assuring a correct location of said elements within the carton, and greatly expediting the packing operation.

A further object is to so bend and fashion opposite end portions of said supporting sheet, as to utilize said end portions as special packing elements.

Still another object is to compressively stress one of said special packing elements between a wall of the carton and the vacuum cleaner, so as to urge the latter firmly against a seat on the opposing wall, formed by another packing element.

Other objects are to utilize the dust bag of a vacuum cleaner as a packing for the body thereof, to hold the wheels of the cleaner suitably spaced above the carton bottom by engagement beneath the cleaner body of a tubular fibre board element, capable of considerable resilient play, and to employ a single fibre board element to form a packing beneath the suction nozzle of the cleaner and between said nozzle and three adjacent walls of the carton.

These and various other objects the invention attains by the construction hereinafter described and illustrated in the accompanying drawings, wherein:

Fig. 1 is a top plan view of the improved carton, with its top-forming flaps folded back to disclose the packing unit, a vacuum cleaner being indicated in dash lines, in the carton.

Fig. 2 is a vertical sectional view of the carton, showing the same closed, the plane of section being indicated at 2-2 in Fig. 1, the cleaner being again shown in dash lines.

Fig. 3 is a top plan view of the packing unit as it appears before insertion in the carton.

Fig. 4 is a side view of the same.

In these views, the reference character 1 designates a carton, formed in any desired manner, of corrugated fibre board. As illustrated, the top and bottom of the carton are each formed by two pairs of opposed flaps 2, formed integrally

with the side walls and meeting substantially midway between said walls.

Packed in said carton is a vacuum cleaner body, comprising a fan housing 3, a suction nozzle 4 extending forwardly and downwardly from said housing and having its lower portion elongated transversely of the body, a motor casing 5 rearwardly projecting from said housing, a pair of forward wheels 6 mounted on said nozzle near its ends, a pair of rear wheels 7 carried by a bracket 8 fastened to the motor casing, therebeneath, and projecting rearwardly therefrom, and a handle-mounting yoke 9 straddling the motor casing and pivoted thereon at 10.

The nozzle rests upon a corrugated fibre board element 11, formed of double thickness stock, which has an upturned portion 12 interposed between the front face of the nozzle and the adjacent wall of the carton. A pair of tongues 13 projecting transversely to the portion 12 from the ends thereof are engaged between the ends of the nozzle and the adjacent walls of the carton.

Beneath the motor casing and transversely thereto is positioned a tubular fibre board packing element 14, which coacts with the inlet end of the nozzle to support the cleaner body, maintaining both the forward and rear wheels spaced well above the carton bottom. Seating of the body on the element 14 is preferably effected through the bracket 8, as clearly appears in Fig. 2.

Another tubular fibre board packing element 15, of an approximate rectangular form, is disposed transversely to the cleaner body between the motor casing and the carton top, the width of said element preferably considerably exceeding its height, so that its seating faces may be desirably large.

To hold the cleaner firmly against forward or rearward movement in the carton, there is provided a packing element 16, formed by a rectangular section of fibre board folded to a double thickness and fitted tightly between the rear portion of the cleaner body and the opposing wall of the carton. Said element is elongated transversely of the body, so as to terminally have positioning engagement with the side walls of the carton, and it is preferred to engage the fold-forming edge of said element in an acute angle formed between the bracket 8 and motor casing, as clearly appears in Fig. 2. Preferably the two thicknesses formed by the element 16 are positively secured in a face-to-face relation by means of staples 17 or an equivalent connection.

A unit assembly for all of the elements 11, 14, 15, and 16 is established by attaching said ele- 53

ments to a supporting sheet 18 formed of corrugated fibre board. Said sheet comprises a portion 19 adapted to seat upon and fully cover the carton bottom, portions 20 and 21, differentially rising against opposite walls of the carton, and an extension 22 from the portion 21, adapted to bear against the carton top. The element 15 is formed integrally with the extension 22, upon the under face thereof, the top wall of said element lying against said extension and forming with the latter a double thickness, and the two thicknesses being permanently interconnected by staples 23 or the like. Preferably, also, a terminal margin of the sheet 18 is bent to interiorly engage a lateral wall of the element 15, reinforcing said wall, as indicated at 24. The element 16 is preferably in the nature of an integral projection from the upper edge of the portion 20. As is apparent from Figs. 3 and 4, the sheet 18 is considerably elongated by its successive formation of the several portions 22, 21, 19, 20, and the element 16, folding creases 25 being preferably machined across said sheet between said portions and between the portion 20 and element 16, to facilitate proper insertion of the unit in the carton. The elements 11 and 14 are attached to the bottom-engaging portion 19 of said sheet in proper spaced relation, preferably by means of staples 26.

The supporting sheet 18, in addition to establishing the packing elements 11, 14, 15 and 16 in a unitary relation, assuring their accurate and expeditious location within the carton, quite strongly reinforces the carton, and forms a shock-absorbing packing member.

The handle-mounting yoke 9 rests upon the element 16, when the packing unit is in place, and to avoid any upward swinging of said yoke on its pivots, it is desirable to interpose suitable packing between said yoke and the carton top. As such a packing the dust bag 27 of the cleaner may be utilized, by extending upon said bag an elongated sheet of freely flexible corrugated fibre board, and rolling said sheet together with the bag into compact, approximately cylindrical form. The possibility of marring or scratching the finish of the cleaner body through contact of its top face with the packing unit is eliminated by interposing a small wax-treated sheet 29 of corrugated fibre board between the cleaner body and the overlying portions of said unit.

In minimizing the requisite number of packing elements, and establishing the majority of said elements in a unitary relation, the described construction effects a very material reduction in the expense of packing vacuum cleaners for shipment.

The invention is presented as including all such modifications and changes as properly come within the scope of the following claims.

What we claim is:

1. In a shipping carton for a vacuum cleaner body having supporting wheels and a suction nozzle, the combination with a fibre board container comprising a top, a bottom, and opposed walls, of a resilient tubular packing element retained within said container adjacent to the bottom thereof, and adapted to underlie said body to elevate the wheels thereof above the container bottom, a second tubular packing element retained within the container adjacent to the top thereof, forming a cushion between said body and top, and a fibre board packing element retained within said container adjacent to a wall thereof, and stressed between said wall and said body to urge the nozzle toward an opposed wall of the container.

2. In a shipping carton for a vacuum cleaner

body, the combination with a fibre board container comprising a top, a bottom, and opposed walls, of a fibre board packing unit inserted in said container and having a portion engaging the container bottom for underlying said body and a portion upstanding against a wall of said container, said unit further comprising a tubular packing element secured to said underlying portion and forming a support for said body, and a packing element carried by said upstanding portion for spacing said body from said upstanding portion.

3. In a fibre board shipping carton for a vacuum cleaner body having a pivotal handle-mounting yoke, a fibre board packing element supported adjacent to a wall of said carton and adapted to extend in approximate parallelism with the carton bottom between said wall and said body, said body providing a support for said element remote from said wall, and said element forming a support for said yoke, and a dust bag attachable to said body and interposed, in rolled form, between said yoke and the carton top, as a packing element.

4. In a fibre board shipping carton for a vacuum cleaner body, a packing unit comprising a fibre board sheet carrying at one end thereof a tubular packing element engageable between said body and one of two opposed walls of the carton, and carrying upon an intermediate portion thereof of a second tubular packing element adapted to be interposed between said body and the other of said opposed walls, and having its other end portion bent into approximate parallelism with said opposed walls and forming a strut between said body and a carton wall transverse to said opposed walls.

5. In a shipping carton for a vacuum cleaner body, the combination with a fibre board container comprising a top, a bottom, and opposed walls, of a packing unit comprising a fibre board sheet having a portion engaging the container bottom, upstanding portions engaging said opposed walls, an extension from one of the upstanding portions engaging the container top, said unit further comprising a tubular packing element carried by said extension and forming a cushion between the cleaner body and the container top, a tubular packing element secured to that portion of said sheet engaging the container bottom and forming a cushioning support for said body, and a fibre board packing element carried by the other end portion of the sheet and engageable between said body and one of said opposed walls.

6. In a carton having a top, a bottom, and opposed walls for shipping a vacuum cleaner body having a suction nozzle adapted to extend adjacent to the carton bottom and to face one of the opposed walls, and elongated between two other walls of the carton, of a packing unit comprising a fibre board sheet having a portion engaging the carton bottom, upstanding portions engaging opposed walls of the carton, an extension from one of said upstanding portions engaging the carton top, said unit further comprising a tubular packing element carried by said extension and forming a cushion between said body and the carton top, a fibre board packing element carried by the other end portion of said sheet and engageable between said body and a wall of the carton, and a fibre board packing element secured to said sheet and having a portion adapted to underlie said nozzle, and a portion adapted for insertion between the nozzle and the wall which

it faces, and portions adapted for insertion between the nozzle ends and adjacent walls of the carton.

7. In a carton comprising a top, a bottom, and opposed walls for shipping a vacuum cleaner body having supporting wheels and a suction nozzle, the combination with a fibre board container comprising a top, a bottom, and opposed walls, of a packing unit comprising a fibre board sheet having a portion engaging the container bottom, upstanding portions engaging opposed walls of the container, and an extension from one of said upstanding portions engaging the container top, said unit further comprising a tubular
- packing element carried by said extension and serving as a cushion between said body and the container top, a fibre board packing element carried by the other end portion of said sheet and engageable between said body and a wall of the container, and fibre board packing elements secured in spaced relation to that portion of said sheet engaging the container bottom, one of the last mentioned elements being adapted to underlie said nozzle, and the other being adapted to underlie and elevate said body, whereby said wheels are spaced above the container bottom. 5
